PILE DRIVING MEASURING INSTRUMENT

August Byron Hunicke, Spring Hill, Ala.

Application May 5, 1947, Serial No. 745,897

6 Claims. (Cl. 73—84)

1

This invention relates to the measuring of the distance a load bearing pile is to be driven into the ground. In particular, the invention is directed to an instrument for indicating automatically when a pile has been driven a sufficient distance.

Piles for supporting the weight of buildings, bridges, piers, and other structures are each required to carry a certain precalculated load. As a pile is driven downwardly, the resistance to the driving force increases with the depth. Driving is continued until it is calculated that this resistance to penetration is greater than the equivalent weight of the load to be carried ultimately by the pile. One of the commonly known ways of calculating this resistance is by the empirically derived "Engineering News Formula" expressed as $L=2E/(S+C)$ wherein L is the bearing capacity or load to be carried, E is the energy expended in driving the pile, S is the set or penetration gained, and C is a constant of the value 1 for drop hammers and 0.1 for steam hammers.

Practical difficulties are encountered in obtaining the values to be used in solving this formula for the unknown S , as the load L and the energy E applied by the hammer are determinable. The usual practice is to mark off roughly equal intervals on the pile with a piece of chalk, and then, while sighting the chalk marks across some object, count the number of hammer blows required to sink the pile from one mark to the next. When the average penetration S per hammer blow used in solving the formula gives a figure not less than the required load bearing capacity for the pile, driving is stopped, and the pile is considered good and safe up to that loading.

This method has the following disadvantages which produce inaccurate results. The intervals marked with chalk on the pile are not always equal due to carelessness in laying them out, and it is substantially impossible for even an experienced man to count the blows given by a steam hammer working at up to 150 blows per minute while trying to sight accurately the position of the marks on the pile, or to make a quick decision as to which blow to call the last when the marks have been made thick with dull pointed chalk. The possibility of human error increases with the operator's inexperience and inefficiency, and once the pile is driven there is scarcely any way in which the accuracy of the work can be checked. As a precaution, piles are often overdriven with a consequential unnecessary expenditure of time and labor, and even destruction of the pile because of being overdriven.

2

The objects of this invention are to produce a mechanism which will assure accuracy in determining the penetration gained in driving a pile per blow of a hammer, eliminate human error, save time and lessen construction costs by increasing the number of piles which can be driven in a given time, make a permanent record of the result of the driving of each pile, and automatically and mechanically doing the observing and indicating necessary to determine whether a pile has been driven sufficiently.

Generally, these objects are accomplished by constructing a mechanism including an electrical circuit in which the electrical equivalents of the hammer blows and penetration of the pile are made dependent upon the actual driving of a pile, and the actual load bearing capacity of the pile indicated at any time by the mechanism in calibrated terms as a function of the changing electrical values in the circuit therein.

The means by which the objects of the invention are obtained may be more fully understood with reference to the accompanying drawings in which:

25 Figure 1 is a diagrammatical view illustrating the application of the invention to the driving of a pile;

Figure 2 is a diagram of a modified form of the invention when used in connection with single acting steam hammers;

Figure 3 is a diagram of a modified form of the invention when used with drop hammers; and

Figure 4 is a diagram of a modified form of the invention when used with double acting steam hammers.

In Figure 1 a pile 2 is shown being driven by a hammer 4. An arm 6 is secured by any convenient means such as nails 8 to the pile. Mounted adjacent the pile is an endless belt 10 which passes over a head sheave 12, parallel to the pile 2, around a tail sheave 14, over take-up rolls 16 and 18, at least once around a drum 20, and thence to head sheave 12. Arm 6 is clamped to the portion of belt 10 which extends parallel to pile 2. As pile 2 is driven downwardly under the impact of hammer 4, arm 6 moves belt 10 which rotates drum 20. This latter is connected through gears 22, shaft 24 and gears 26 to the movable element 28 of a rheostat 30. The rotation of drum 20 thus serves to vary the rheostat 30.

An electrical circuit connected to rheostat 30 includes in series a resistance 32, batteries 34 and 36 coupled in parallel, ammeter 38 and switch 40. A tape recorder 42 is connected to ammeter 38,

and an indicator 44, which may be in the form of a horn, bell, light or whistle, is likewise connected to the ammeter.

Switch 40 may be actuated by a solenoid 46 which in turn is energized by a time relay 48, 6 said relay being set by movement of the shaft 24 through gears 50 and shaft 52.

The "Engineering-News Formula"

$$L=2E/(S+C)$$

dropped varies, and consequently the value E in the formula becomes a variable. In Figure 3 the hammer 4 is actuated by a cable 10 passed over head pulley 12. This pulley is connected by a shaft 14 to speed and travel ratio gears 16 which are geared to the movable arm in rheostat 18. The force, or voltage, from battery 38 is thus adjusted by this variable resistance to the equivalent of the height to which the hammer 4 is pulled before it is dropped. Any mechanical means may be provided in the gear system connecting pulley 12 with rheostat 18 so that the setting of the rheostat is not changed as the hammer drops, and similarly means may be provided for returning the rheostat setting to zero after each recording has been made. Otherwise, the circuit and its operation are as in Figure 1.

In double acting steam hammers, the formula becomes $L=2W+2aph/(S+C)$ wherein a is the piston area, p is the cylinder pressure and h is the length of the piston stroke. Figure 4 shows the manner in which the electrical equivalents are achieved in this invention. The double acting hammer 80 has its pressure cylinder in communication with a bellows 82 by means of the conduit 84. The bellows operates a rod 86 connected to an eccentric plate 88 which carries the arm 90 of the rheostat 92. The battery 34 represents the force applied to the hammer by the pressure cylinder, this force being modified by the rheostat 92. The rheostat and battery are coupled in parallel with battery 36, a switch 94 being provided to deactivate this coupling when desired. The system otherwise operates as described for Figure 1. It is evident that the source of pressure for the bellows 82 may be from the boiler, or air compressor, which furnishes the pressure for the pressure cylinder in the hammer 80, rather than the direct connection to the hammer as shown. Similarly other equivalent means may be used to vary the rheostat 92 in order to introduce the value of $2aph$ into the circuit.

The invention is especially useful in the driving of piles under water as the attachment of the endless belt 10 to the pile presents no difficulties. The mechanism can be attached to any kind of pile, at any point along the length of a pile, and is easy to mount in the leads of the pile driver.

Having now described the means by which the objects of the invention are achieved,

I claim:

1. An apparatus for determining the load bearing capacity of a pile while driving said pile by successive impact forces, each of which causes the pile initially to move downwardly, followed immediately by an upward counter movement and then by a further downward movement to the final set of said pile, comprising means for completing an electrical circuit in which the current flow is varied in response to movements of said pile under successive driving impact forces, means electrically connected to said circuit for visually showing said current variation as a function of the movement of said pile, and means actuated by said movements for delaying the variation in current until the pile reaches final set after each impact force.

2. An apparatus for determining the load bearing capacity of a pile while driving said pile by successive impact forces, each of which causes the pile initially to move downwardly, followed immediately by an upward counter movement and then by a further downward movement to the final set of said pile, comprising means for producing an electrical current, means for varying

simply states that the bearing capacity is equal to a force E divided by a resistance S. This is the expression as in Ohm's law in which amperes are equal to volts, a force, divided by ohms, a resistance. Therefore, the formula can be expressed as $L=V/S+C$, and in the electrical circuit of Figure 1, L is represented by the ammeter 38, V by the batteries 34 and 36, S by the rheostat 30 and C by the resistance 32.

When the pile is to be tested for the penetration being gained, arm 6 is coupled to belt 10, and the pile struck by hammer 4. The distance the pile is driven by each blow varies the setting of arm 28 in rheostat 30 and thus varies the resistance in the electrical circuit and the current flow registered by ammeter 38. This in turn actuates tape recorder 42 which may be calibrated to record in tons the load bearing capacity of the pile. A permanent record is thus obtained of the allowable load bearing capacity of the pile at the time driving is stopped. By testing the pile at regular intervals during the driving, it can be assured that the pile will not be overdriven, and that the driving can be stopped as soon as the proper readings are obtained, with a resulting saving of time. The indicator 44 is set to make a signal when a certain load value is reached and thereby calls attention to the fact that a pile has been driven sufficiently. Recorder 42 can show the difference between additive successive hammer blows, or alternatively means may be provided to return arm 28 of rheostat 30 to zero position following each hammer blow.

The switch 40 is held open by solenoid 46 until arm 28 has come to rest at the value determined by the set of the pile after each hammer blow. There is an increment of time between the instant of the hammer blow and the rest position of the pile in which the pile is moving, and this time is greater when the pile is driven in soft ground. Upon each impact, the pile moves downwardly, then bounces upwardly a fraction of the downward distance, and then settles to its final set. Consequently, each movement of the pile actuates the time delay relay 48 which in turn energizes solenoid 46, at the instant the pile stops moving and is at its final set, to close switch 40, and cause a recording to be made or signal given.

In Figure 1, the batteries 34 and 36 indicate the voltage sources needed for measuring the force applied by either single acting or double acting steam hammers. For a single acting steam hammer the formula is $L=2Wh/(S+C)$ wherein W is the weight of the hammer and h is height of the fall of the hammer. Figure 2 illustrates the modification of the circuit to include this value. Only a single current source 36 is included, its force, or voltage, being regulated to a constant value representing the value Wh by setting the rheostat 60. The setting on this resistance can be used to proportion the voltage from source 36 to suit a variety of hammer sizes.

When the device is used for drop hammers, it is observed that the height the hammer is

the current so produced in response to movements of said pile under successive driving impact forces, means actuated by said movements for delaying the start of current flow through said varying means until the pile reaches final set after each impact force, and means for visually showing said current variation as a function of the movement of said pile.

3. An apparatus for determining the load bearing capacity of a pile comprising in series circuit a rheostat, a resistance, a voltage source, and an ammeter, means actuatable by said pile for varying said rheostat in response to increments of movement of said pile during the driving of the same, and time delay switch means actuatable by each initial movement of said rheostat varying means for completing said circuit after the pile has reached final set under a hammer blow.

4. An apparatus as in claim 3, in which said rheostat varying means comprises an endless belt 20 a portion of which is adapted to extend parallel to the length of the pile, means for securing said portion to a pile, and means for transmitting motion of said belt to said rheostat.

5. An apparatus as in claim 3, said time delay 25 switch means comprising a switch in the electrical circuit including said ammeter, and a time relay for actuating said switch in response to movements of said pile.

6. An apparatus for determining the point at which a pile being hammer driven has reached a desired load bearing capacity, comprising an electrical circuit composed of voltage means, rheostat means actuatable by said pile for varying the current produced in said circuit as a function of the movement of said pile, time delay means for delaying energizing of said circuit until after the pile reaches final set, and means actuated by said current flow through said circuit for indicating the load bearing capacity of said pile as a function of the distance said pile is moved to final set.
